US00D497160S1

(12) **United States Design Patent** (10) Patent No.: **US D497,160 S**
(45) Date of Patent: **** Oct. 12, 2004**

(54) **MOBILE POS**

(75) Inventors: **Eiji Nagao, Ichikawa (JP); Takayuki Kakizaki, Saitama (JP); Seiji Tomita, Kawasaki (JP); Youhei Shimura, Ota (JP)**

(73) Assignee: **Fujitsu Limited, Kawasaki (JP)**

(**) Term: **14 Years**

(21) Appl. No.: **29/159,453**

(22) Filed: **Apr. 23, 2002**

(30) **Foreign Application Priority Data**

Oct. 25, 2001 (JP) 2001-031274

(51) LOC (7) Cl. **14-03**

(52) U.S. Cl. **D14/346; D14/138**
